Patented Oct. 29, 1912.

UNITED STATES PATENT OFFICE.

DAVID W. DORRANCE, OF KOLER, OREGON.

ARTIFICIAL HAND.

1,042,413.

Specification of Letters Patent. Patented Oct. 29, 1912.

Application filed February 17, 1912. Serial No. 678,401.

To all whom it may concern:

Be it known that I, DAVID W. DORRANCE, a citizen of the United States, and a resident of Koler, county of Douglas, State of Oregon, have invented a new and useful Improvement in Artificial Hands, of which the following is a specification.

My present invention has for its object the providing of a device which is inexpensive to manufacture, convenient to affix on an arm-stump, and likewise convenient to use; also to make the operation of my improved hand similar to the gripping action of the fingers of the human hand; also 15 to adapt my artificial hand to be used for many and various uses, especially to firmly hold objects and implements, particularly table implements and working tools.

The construction, operation and attachment of my device are illustrated in the accompanying drawings constituting a part of this specification.

In such drawings: Figure 1 is a perspective of my artificial hand showing it as attached to a human arm-stump, and showing the device so operated, by the bending of the arm at the elbow, that implements may be inserted between the fingers of my artificial hand; this figure further showing, in broken outline, the position of the parts when the arm-stump is moved to the position required to cause the automatic closing of the fingers of my device, and in so doing firmly grasping the implement inserted between the 25 fingers; Fig. 2 is a side elevation in perspective of my artificial hand, illustrating the mode in which, for example, a knife is held thereby; Fig. 3 illustrates my artificial hand as holding an umbrella; and Fig. 4 is a 30 detail of the means rotatably holding the main finger of my artificial hand to the extremity of the socket or case which is affixed to the arm-stump.

My hand is formed with a wrist disk *w*, by 35 which it is rotatably supported on the extremity of the case or socket *b*. See Fig. 4. The main finger, *a*, of my hand is an integral part of said wrist disk *w*. The case or socket *b* is adapted to be affixed on the human arm-stump, as usual, and is secured in place by straps, as shown at *o*. The main finger, *a*, is provided at *c* with a hinged knuckle, in which is hinged the movable finger *d*. Both 50 fingers are made with hook-shaped extremities of the same radius, and preferably so

made that when the two fingers are together, without holding any object, they will form, in cross section, a circle, and that each of said hooked extremities constitute a half circle in cross section, with their flat faces 55 opposed to each other. The flat inner surfaces of the fingers gives a better hold on the implements to be held.

At *e* I provide an elastic agent or retractive means. I find it very convenient to use 60 for this purpose a plurality of rubber bands encircling both fingers, *a*, *d*, near the knuckle joint *c*, and providing some means, *e. g.*, a projecting pin *f*, for holding the bands against displacement. These, however, of 65 course are mere details of construction, although my experiments have shown that there is a superior property apparently in rubber bands over ordinary metallic springs, when applied to the use I put them to in my 70 invention.

On the movable finger, *d*, is provided a perpendicular member *g*, serving the purpose of a thumb, as it were, being concave on its inner face, so as to afford a better 80 hold on the implement gripped by my artificial hand. The extremity of the member *g* is formed with an eye *h*, in which is fastened a cord, *i*, the upper end of which is inserted under the fastening strap, *o*, of the 85 casing or socket *b*, and fastened to a shoulder piece as at *s*, in Fig. 1.

The movement of the stump of the forearm, into extended position, would cause separation of the fingers, *a*, *d*, as illustrated 90 in Fig. 1, and by bending the forearm, as indicated by broken outline in the same figure, said fingers would be brought together by the contracting action of the rubber bands, and thus the fingers caused to firmly 95 grip the implement.

The manner in which the implement is held is illustrated in Fig. 2, the handle *j* of the knife shown bearing against the inner concave face of the member *g* of the movable finger, and the blade of the knife *k* being held between the flat inner surfaces of the fingers *a*, *d*.

In order to give to my artificial hand a more pleasing appearance, it may be incased in 105 a glove-like casing, as shown at *m* in Fig. 3.

It will be noted that my artificial hand may also be used as an ordinary rigid hook by merely detaching the strap *i*. And it will 110 also be noted that my artificial hand may be

readily applied to the end face b' of the many types of commercial casings or sockets, like b , now on the market.

I claim:

- 5 1. An artificial hand comprising a socket
adapted to be fastened on the stump of an
amputated arm; a rigid finger projecting
from the extremity of said socket; a movable
10 finger hinged to the rigid finger and match-
ing with and normally closed on said rigid
finger; a rigid perpendicular member on
said movable finger to form a seat against
which an article held by the artificial hand
15 is supported; a cord fastened at one end to
said rigid member for fastening at its op-
posite end to the shoulder of the wearer,
means, comprised in said socket and its fas-
tening means, for guiding said cord at the
20 joint of the elbow of the amputated arm;
and means for normally closing the mov-
able finger on the rigid finger.

2. An artificial hand comprising a socket
adapted to be fastened on the stump of an
amputated arm; a rigid finger projecting
25 from the extremity of said socket; a movable
finger hinged to the rigid finger and match-
ing with and normally closed on said rigid
finger; a rigid perpendicular member on
said movable finger to form a seat against
30 which an article held by the artificial hand
is supported; said rigid member formed
near its free end with a concave inner face;
a cord fastened at one end to said rigid mem-
ber for fastening at its opposite end to the
35 shoulder of the wearer, means, comprised in
said socket and its fastening means, for
guiding said cord at the joint of the elbow
of the amputated arm; and means for nor-
mally closing the movable finger on the rigid
40 finger.

3. An artificial hand comprising a socket
adapted to be fastened on the stump of an
amputated arm; a rigid finger projecting
45 from the extremity of said socket; a mov-
able finger hinged to the rigid finger; a rigid
perpendicular member on said movable fin-
ger; said rigid member formed with a con-
cave inner face; a cord fastened at one end
50 to said rigid member for fastening at its
opposite end to the shoulder of the wearer,
means, comprised in said socket and its fas-
tening means, for guiding said cord at the
joint of the elbow of the amputated arm;
55 and a rubber band encircling said fingers
in front of said hinge joint.

4. An artificial hand comprising a socket
adapted to be fastened on the stump of an
amputated arm; a plate rotatable in the ex-
60 tremity of said socket, a rigid finger project-
ing from said plate; a movable finger hinged
to the rigid finger and matching with and
normally closed on the rigid finger; the ex-
tremity of said fingers when together forming
65 a hook; the inner opposite faces of said
fingers made flat; a rigid perpendicular

member on said movable finger; said rigid member formed with a concave inner face; a cord fastened at one end to said rigid member for fastening at its opposite end to the shoulder of the wearer, means, comprised in said socket and its fastening means, for guiding said cord at the joint of the elbow of the amputated arm; and means for normally closing the movable finger on the rigid finger.

70

5. An artificial hand comprising a socket adapted to be fastened on the stump of an amputated arm, a plate rotatable in the extremity of said socket, a rigid finger projecting from said plate, a pivoted finger co-operating with and matching the stationary finger at the free end, the pivoted finger having an extension the end of which terminates beyond the plane of the pivoted finger and serves as a support against which an article bears when gripped between the fingers, and means for operating the pivoted finger.

80

6. An artificial hand comprising a socket adapted to be fastened on the stump of an amputated arm; a plate rotatable in the extremity of said socket, a rigid finger projecting from said plate; a movable finger hinged to the rigid finger; the extremity of said fingers formed hook-shaped; the inner opposite faces of said fingers made flat and each of said fingers representing approximately a half circle in cross section; a rigid perpendicular member on said movable finger; said rigid member formed with a concave inner face; a cord fastened at one end to said rigid member for fastening at its opposite end to the shoulder of the wearer, means, comprised in said socket and its fastening means, for guiding said cord at the joint of the elbow of the amputated arm; and a rubber band encircling said fingers in front of said hinge joint.

502

7. An artificial hand comprising a socket adapted to be fastened on the stump of an amputated arm; a plate rotatable in the extremity of said socket, a rigid finger projecting from said plate, said finger provided with a hinged knuckle; a movable finger hinged to said hinged knuckle of the rigid finger and matching with and normally closed on said rigid finger; the extremity of said fingers when closed forming a hook; the inner opposite faces of said fingers made flat and each of said fingers representing approximately a half circle in cross section; a rigid perpendicular member on said movable finger to form a seat to support an article held by the artificial hand; said rigid member formed with a concave inner face; a cord fastened at one end to said rigid member for fastening at its opposite end to the shoulder of the wearer, means, comprised in said socket and its fastening means, for guiding said cord at the joint of the el- 130

115

bow of the amputated arm; and means for normally closing the movable finger on the rigid finger.

8. A device of the character described comprising a pair of hook-shape fingers, one of which is pivotally mounted, the hook ends of said fingers matching, means for normally drawing the fingers together, the pivoted finger having a projection which extends away from the hook ends of the fingers, means for securing the device to an arm stump, and means extending from the pivoted finger for operating the same.

9. A device of the character described comprising a pair of matching fingers, one of which is pivotally mounted, the pivoted finger having an extension, the end of which terminates beyond the plane of the pivoted finger and serves as a support against which an article bears when gripped between the fingers, means for normally closing the fingers, means for operating the pivoted finger, and means for securing the device to an arm stump.

10. A device of the character described, comprising a stationary finger formed at its free end with a lateral extension, a second finger pivoted to the stationary finger and

formed at its free end with a lateral extension which contacts with the lateral extension of the companion finger to form gripping jaws, the pivoted finger having a seat formed on one surface in rear of the lateral extension to provide a support for an article being held by the jaws, means for normally closing the fingers, and means extending from the pivoted finger to operate the same.

11. A device of the character described, comprising a stationary finger formed at its free end with a curved hook, a finger pivoted to the stationary finger and formed at its free end with a curved hook, an upward and outwardly projecting support extending from the pivoted finger in rear of the curved hooked end and from the inner surface of the said finger, the upward extended portion of the support being inside the plane of the inner curved surface of the curved hook, means for normally closing the pivoted finger on the stationary finger, and means for operating the pivoted finger for gripping an article.
